CLAIM

The ornamental design for a collapsible tub, as shown and described.

DESCRIPTION

FIG. 1 is a front, top perspective view of a collapsible tub, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled 9 in FIG. 1; and,

FIG. 10 is an enlarged view of the area labeled 10 in FIG. 7.

The broken lines show portions of the collapsible tub that form no part of the claimed design.

The dashed lines in the figures illustrate portions of the collapsible tub that form no part of the claimed design.

The dash-dot broken lines represent stitching that forms no part of the claimed design.

The dot-dash broken lines of the collapsible tub in FIG. 1 illustrate a boundary and cut line of the enlarged view in FIG. 9 and form no part of the claimed design.

The dot-dash broken lines of the collapsible tub in FIG. 7 illustrate a boundary and cut line of the enlarged view in FIG. 10 and form no part of the claimed design.
